SPRING SASH BALANCER

Christopher C. Amy and Harry B. Harding,
Reno, Nev.

Application April 27, 1951, Serial No. 223,406

1 Claim. (Cl. 292—76)

1

This invention relates to a window construction, and more particularly to a sash balancer for a window.

The object of the invention is to provide a spring sash balancer which will effectively retain the window sashes immobile in their various adjusted positions.

Another object of the invention is to provide a spring sash balancer which can be mounted in a conventional window or a window having removable sashes, the balancer of the present invention enabling the window sashes to be raised with ease, and wherein accidental lowering of the sashes is prevented.

A further object of the invention is to provide a spring sash balancer which is extremely simple and inexpensive to manufacture.

Other objects and advantages will be apparent during the course of the following description.

In the accompanying drawings forming a part of this application, and in which like numerals are used to designate like parts throughout the same:

Figure 1 is a horizontal sectional view taken through a window, showing the sash balancer of the present invention installed therein;

Figure 2 is a fragmentary side elevational view of the window construction, with parts broken away and in section;

Figure 3 is an enlarged fragmentary end elevational view of the window sash, showing the balancer of the present invention therein;

Figure 4 is a sectional view taken on the line 4—4 of Figure 2;

Figure 5 is a sectional view taken on the line 5—5 of Figure 2.

Referring in detail to the drawings, there is shown a window construction wherein the frame includes the stops 10 that are vertically disposed and which may be fabricated of any suitable material. The window further includes the usual casing 11 and window sills 12. There is further provided a pair of spaced parallel, vertically disposed side jambs 14 and 15. The first jamb 14 is provided on its inner face with a pair of recesses 16 and 17, Figure 1, and arranged contiguous to the inner face of the first jamb 14 is a metal jamb liner 18. The liner 18 includes an intermediate flat portion 19 and a pair of curved portions 20 which seat in the recesses 16 and 17.

Mounted for sliding movement or up-and-down movement in the window frame is a lower window sash 21 and an upper sash 22. Since each of these sashes 21 and 22 is of the same

construction, only one will be described in detail. The upper sash 22 includes a pair of spaced parallel side rails 23 and 24, and extending between these siderails and secured thereto is a window pane or glass 25. The side rail 23 is provided with a longitudinally extending shoulder 26 on its outer surface which rides or slides in the curved portion 20 of the liner 18.

The other jamb 15 is provided with a plurality of spaced parallel, longitudinally extending grooves or cutouts 27 which define therebetween webs or fingers 28. The outer face of the side rail 24 is bifurcated or provided with a cutout or groove 29, and this cutout 29 defines a pair of fingers or tongues 30 which slide in the cutouts 27, the web 28 projecting partially into the cutout 29.

Arranged in each of the cutouts 29 is the spring sash balancer which serves to maintain the window sashes immobile in their various adjusted positions, the spring sash balancer being indicated by the numeral 31. The spring sash balancer 31 includes a first plate 32 that may be made of any suitable material, such as spring metal, and the plate 32 includes a central flat portion 33 which is arranged contiguous to the adjacent surface of the side rail 24. The plate 32 is further provided with an outwardly bowed flexible portion 34, and there is further provided a second outwardly bowed flexible portion 35. The bowed portion 35 is arranged above the flat lower end 36 of the plate 32. These features are shown clearly in Figure 2.

The spring sash balancer further includes a spring member 37 which includes a central portion 38 that is flat, the central flat portion 38 being provided with a slot 39. A suitable securing element, such as a screw 40, projects through the slot 39, through the plate 32, and into the side rail 24. The slot 39 permits the spring member 37 to slide up and down relative to the plate 32. The spring member 37 is further provided with an upper flexible bowed portion 41 and a lower bowed portion 42, the portions 41 and 42 slidably engaging the web 28.

In use, the spring sash balancer of the present invention will serve to maintain the window sashes immobile in their various adjusted positions. It is to be understood that one of the spring sash balancers is provided for each of the window sashes. Thus, the spring sash balancer 31 will maintain the upper sash 22 immobile in its adjusted position and will not interfere with normal manual raising or lowering of this window sash. When the window sash 22 is not moving or

when it is stationary, the bowed portions 41 and 42 of the spring member 37 will bear against the web 28 to prevent accidental sliding movement of the sashes. Then, when the window sash 22 is raised, the spring member 37 will slide downwardly relative to the plate 32. Thus, the flat intermediate portion 33 and the lower flat portion 36 of the plate 32 will permit the ends of the spring member 37 to move downwardly along the plate 32, so that the window sash 22 can be easily raised. However, to prevent accidental lowering of the window sash 22, it will be seen that not only do the bowed portions 41 and 42 bear against the webs 28, but also the ends of the spring member 37 will engage the bowed portions 34 and 35 during the lowering movement. Thus, during lowering of the window sash 22, the bowed portions 34 and 35 will help increase tension or provide resistance against this lowered movement. The window sash 22 can be readily removed if desired by manually moving the window sash 22 to the left, Figure 1, so that the spring sash balancer will be compressed, whereby the right side of the window sash 22 can be disengaged from the jamb 14 and removed.

However, it is to be understood that the spring sash balancer can be installed in various types of windows, and the balancer permits the sashes to be raised with ease, but the balancers prevent the sashes from dropping down when wet or dry. The jamb 15 may be of one-piece construction, and the liner 18 may be made of metal. The tension on the spring balancer is released when the sash is raised up, and the tension is increased when the sash is lowered, so that the sash will not accidentally drop down.

The sash balancer of the present invention further includes a coil spring 43, Figure 2, which serves to increase the tension when the sash is lowered. Further, the spring 43 acts as a safety

5 which insures that the spring member 37 will always be pulled upwardly when the sash is lowered, thus insuring that there will be increased tension when the sash is lowered. One end of the coil spring 43 is connected to a projecting portion 45 on the spring member 37, while the other end of the coil spring 43 is connected to a portion 44 that projects from the plate 32.

10 What is claimed is:

In a spring sash balancer, a first plate including an intermediate flat portion, the upper end of said plate being provided with a first outwardly extending flexible bowed portion, a second outwardly bowed flexible portion on said plate spaced from the bottom thereof, a spring member including a central flat portion provided with a slot, a securing element extending through said slot and through said plate, said spring member being provided with a pair of outwardly bowed 15 spring portions for coaction with the bowed portions of said plate, and a coil spring having one end connected to said spring member and its other end connected to said plate, the ends of said spring member selectively engaging the 20 bowed portions of said plate.
